TARGET AND BACKING MEMBER THEREFOR
Angus Dun, Jr., Fairview Drive, Neshanic
Station, N.J. 08853
Filed Apr. 28, 1964, Ser. No. 363,169
15 Claims. (Cl. 273—102.1)

The present invention relates to a target and a backing member therefor, adapted for use on a rifle range or a pistol range and by the use of which a permanent mark or indication will be clearly visible from the firing line so that the exact point of penetration of the bullet or other projectile will be permanently made on the target.

Another advantage of the present invention is that it will eliminate the necessity of the person using the firearm or anyone else leaving the firing line and approaching the target until the point of penetration can be seen. In addition to the inconvenience of approaching the target to ascertain where the bullet has hit, there is a certain measure of danger to the person approaching the target, since usually a series of such targets are suspended from wires or the like closely adjacent to one another and the person approaching the target might accidentally get in the line of fire of another person using the range.

A further advantage and object of the present invention is to provide a target of this character by the use of which spotting telescopes is eliminated, especially where pistol matches are involved, since the pistol range, that is, the target is usually about sixty-five feet from the firing line. The cost of these telescopes is rather high and some ranges could not afford to purchase a supply of these telescopes.

When used on rifle ranges where the targets are positioned from fifty to one hundred yards from the firing line, use of the present invention would eliminate the necessity of a high powered telescope of say twenty to thirty power, which is necessary with the conventional target, and would permit the use of a spotting telescope of much lesser power and much less expensive.

On some firing ranges, using the conventional targets, instead of making use of spotting telescopes a conventional pulley system for pulling the targets to the firing line for observation is employed, but these pulley systems are very expensive and involve a maintenance cost. The use of the target equipped with the backing member of the present invention will eliminate the need of these expensive pulley systems.

A still further advantage and object of the present invention is to provide a target of this character which will permit the calling of each shot when zeroing in from the firing line. This is true because the exact point of penetration is clearly visible from the firing line.

The backing member of the present invention is fixed to the rear face of the target in alignment with the bull's-eye area of the target and is made of a material which will stretch when being penetrated by the bullet or projectile and will return to its original unstretched condition after the bullet has passed therethrough save for a pin hole or small opening in the center of the area of the backing member through which the bullet has passed. The object of this pin hole or small opening is that in matches or tournament a number of shots, usually about ten, is fired by each contestant and the area covered by the group of shots is determined by measuring from center to center of the punctures or penetrations made by the ten bullets. By producing these pin hole openings for each shot fired the area of the group of shots can be measured with greater precision than when a conventional target is used, since with the conventional target, any overlapping penetrations will tear away the material of the target and it will not be possible to measure from center to center of the ten penetrations.

2

A very important feature of this invention is that it will provide a target having a backing member which will produce a permanent marking or indication on the target which can be examined and studied leisurely by the master, judge or scorer even though the official did not actually see the results of each shot as it was fired.

Another aim of the present invention is to provide a backing member of this type which can readily and easily be affixed to the rear face of a conventional target so that the backing member can be sold as a separate article and the purchaser can apply it to the rear face of the targets. Of course the backing member can also be applied to the rear face of the target by the manufacturer of the target at the time the target is made.

15 The backing member is made of a contrasting color to the color of the bull's-eye, the conventional target has a bull's-eye area, usually in black, so that the backing member of the present invention could be made in the color white. The fact that the portion of the target 20 hit by the bullet is dissipated to an extent approximately equal to the circumference of the bullet and the fact that the backing member has a recovery characteristic to its original condition after the bullet has passed therethrough, except for the pin hole mentioned above, the 25 white backing member will be easily discernible in the portion of the target which has been dissipated by the striking of the bullet against the target.

30 A still further aim of the present invention is to provide a target and a backing member therefor which 35 backing member has only certain areas thereof secured to the rear face of the target so that the unsecured portions of the backing member are free of the target and therefore can stretch the necessary amount when a bullet passes therethrough without detaching the backing member from the target.

With the foregoing and other objects in view, the invention will be hereinafter more fully described and more particularly pointed out in the appended claims.

40 In the drawings in which the same parts are denoted by the same reference numerals throughout the several views,

FIGURE 1 is a front elevational view of a target constructed in accordance with the present invention,

FIGURE 2 is a side elevational view thereof,

45 FIGURE 3 is a rear elevational view thereof,

FIGURE 4 is an exploded side elevation illustrating the method of assembly of the target and the backing member,

50 FIGURE 5 is a series of side elevational views of a target with parts in section to show in sequence the effect of a projectile on the target and backing member as it penetrates the target and the backing member and passes entirely therethrough,

55 FIGURE 6 is an enlarged fragmentary front elevational view of the target illustrating the appearance of the bull's-eye section thereof after being penetrated by a number of projectiles,

FIGURE 7 is a sectional view taken on the line 7—7 of FIGURE 6,

60 FIGURE 8 is a fragmentary vertical sectional view of a modified form of the invention illustrating diagrammatically means for hermetically attaching a backing member to the target at spaced apart points,

FIGURE 9 is a fragmentary rear elevational view 65 taken along the line 9—9 of FIGURE 8,

FIGURE 10 is a rear elevational view with parts broken away of a modified form of backing member,

FIGURE 11 is a vertical sectional view taken on the line 11—11 of FIGURE 10, and

70 FIGURE 12 is a view similar to FIGURE 10 illustrating another form of the backing member.

Referring more particularly to the drawings and especially to FIGURES 1 through 7, at 10 is indicated a target which may be of the conventional type and made of any material which can be penetrated by a bullet or other projectile and may be made of the conventional type target paper. The front face of the target 10 is inscribed with the usual or conventional concentric marking circles 11 which define the outer target areas and the inner concentric marking circles 12 which define the bull's-eye area 13.

As can be seen particularly by FIGURES 2, 3 and 5 of the drawings, a backing member 14 is affixed to the rear face of the target 10 in alignment with the bull's-eye area 13 and the backing member 14 may be made of substantially the same size as the bull's-eye area 13. The backing member 14 may be of any desired thickness but it has been found in actual practice that a thickness of from one-sixtyfourth to three-sixtyfourths of an inch works very satisfactorily. The backing material must be such that it has the characteristic or ability to stretch as the bullet or projectile penetrates it and permit the bullet finally to break through and pass entirely through the backing member and then the backing member will have the ability to recover or snap back to its original unstretched condition except or save for a pin hole or small opening in the center of the area of the backing member through which the bullet has passed. The backing member should be of a color which contrasts with the color of the bull's-eye area. Since the bull's-eye area of a conventional target is black, it is preferred that the backing member be a white color so that there is a sharp contrast between the black bull's-eye and the white backing member after the target and backing member have been penetrated by a bullet.

The backing member could be made of many materials which meet the characteristics set forth above, but the following are some examples of the material which would serve the purpose of this invention, natural rubber, silicone rubber, polyvinylchloride and polyethylene.

The following tabulations give the preferred durometer readings on the Shore A scale and the Shore D scale for the various materials mentioned above. The durometer readings indicate a hardness test, that is, the amount of pressure required to make an indentation on the material being tested.

at spaced apart intervals, as indicated at 15, in FIGURE 7 of the drawings. In the form of the invention illustrated in FIGURES 1 through 7 of the drawings, the adhesive is applied to the backing member in spaced apart 5 concentric circles and may be applied thereto by means of a compass, the writing element of the compass has some of the adhesive applied thereto and the pointed end of the compass is inserted in the backing member at the center thereof and the compass is then rotated to form spaced apart concentric circles of increasing diameter 10 away from the center of the backing member toward the outer peripheral edge thereof.

By applying the adhesive in this manner, the adhesive is applied to a sufficient number of spaced apart areas of 15 the backing member to assure the secure affixing of the backing member to the rear face of the target, leaving the intervening areas of the backing member free from attachment to the target so that when the bullet penetrates the backing member it will be free to stretch until it 20 reaches its breaking point without pulling the backing member from the target.

In the use of the target illustrated in FIGURES 1 through 7, it is assumed that the target 10 with the backing member 14 properly affixed thereto is set up in the conventional manner and the marksman takes his position 25 on the firing line and fires at the target. Assuming that the projectile or bullet thus fired strikes within the bull's-eye area 13 of the target, the effect of the bullet striking and penetrating the target and the backing member is clearly illustrated in the series of views shown in 30 FIGURE 5 of the drawings. Reading the views from left to right when looking at FIGURE 5, the first view shows the initial penetration of a bullet 16 or other projectile through the target 10 and its engagement with the backing member 14 to initiate the stretching of the backing member. The second and third views illustrate further 35 penetration of the bullet 16 through the target and causing further stretching of the backing member. View No. 3 shows the backing member stretched almost to its breaking point and view 4 shows that the backing member has 40 reached its breaking point and the bullet has begun to emerge from the rear face of the backing member. The fifth view of FIGURE 5 shows the final position of the target and the backing member after the bullet 16 has 45 passed entirely therethrough.

The backing member 14 is secured to the rear face of the target 10 by means of any appropriate conventional adhesive, such as, a conventional rubber cement. The adhesive is applied to one face of the backing member 14

75 It will be noted that a portion 17 of the target has been entirely cut away or dissipated by the passage of the bullet 16 therethrough and that this portion has a diameter substantially equal to the external diameter of the

bullet. It will also be noted from the fifth view of FIGURE 5 that the portion of the backing member which was stretched by the passage of the bullet therethrough has fully recovered or returned to its original unstretched condition save for the formation of a small or pinhole 18 which coincides with the center of the cutaway portion 17 of the target. The cutaway portion 17 of the target will expose the now recovered stretched portion of the backing member to the view of the marksman on the firing line and due to the contrasting color of the bull's-eye area and the backing member this exposed area of the backing member will be readily visible by the marksman from the firing line. This exposed area of the backing member 14 and which was stretched by the passage of the bullet therethrough is indicated at 19.

FIGURES 6 and 7 of the drawings illustrate the effect upon the target 10 and the backing member 14 when a round of ten shots penetrate the target and the backing member. From these two Figures it will be noted that the bull's-eye area 13 has had considerable of its material cut away as indicated by the cut away portion 17 and it will be noted that a corresponding amount of the backing member is exposed as indicated at 19. It will be further noted that in this exposed area 19 of the backing member 14, there are ten small or pinhole openings 18 clearly defined and visible although apparently two of the bullets penetrated overlapping portions of the backing member, as can be discerned in the upper part of the area 19. This will permit the accurate measuring of the openings 18 from center to center for the purpose of determining the size of the grouping of shots in order to determine the score of each contestant.

Turning now to FIGURES 8 and 9 of the drawings, we find a modified form of the target and backing member. The target is indicated at 20 and the target areas on the front face thereof are inscribed thereon in the conventional manner. There is applied to the rear face of the target 20 a film or thin coating of natural rubber, silicone rubber, vinyl, polyvinylchloride or polyethylene of the thickness of approximately .002 to .010 inch in thickness. This film of material is laminated directly to the back of the target 20 and is indicated at 21 in FIGURES 8 and 9. The backing member 22 which is similar to the backing member 14 of FIGURES 1 through 7 is hermetically sealed to the exposed surface of the film 21 at spaced apart areas indicated at 23 so that unattached or floating portions 24 are formed or provided between the sealed areas 23 of the backing member 22. These hermetically sealed areas 23 may be formed in any manner by the application of heat at the desired points or areas. In FIGURE 8 is shown diagrammatically at 25 a conventional device for applying the heat to the areas 23. This device 25 includes heating tubes 26 which are brought into contact with the rear face of the backing member 22 at the points or areas at which the sealed areas 23 are desired to be made.

The backing member 22 should be made from the same material as the film or coating 21 so that a good strong hermetical seal is provided at the areas 23 between the film 21 and the backing member 22.

The target illustrated in FIGURES 8 and 9 will be used in the same manner as the target illustrated in FIGURES 1 through 7 and the effect made thereon by a projectile penetrating the target and the backing member will be the same as that described in connection with the target of FIGURES 1 through 7.

In FIGURES 10 and 11 is illustrated a modified form of the backing member which is indicated at 27. The backing member 27 may be made of any of the five materials mentioned above in connection with the backing members 14 and 22 and is of substantially the same thickness as the other backing members.

One face of the backing member 27 is provided with spaced apart concentric circular ribs or ridges 28, the width of which will vary in direct proportion to the diam-

eter of the backing member 27. The exposed outer surfaces of the ribs 28 have applied thereto an adhesive 29 which may be a conventional rubber cement adhesive. A pull-off cover 30 is applied to the ribbed side of the backing member 27 and adheres lightly to the adhesive 29 so as to protect the adhesive from the air, moisture and other extraneous matter which might interfere with the ability of the adhesive 29 to adhere to the rear face of the target when the backing member 27 is applied thereto. This pull-off cover 30 may be a waxpaper or other conventional protective cover used for such purposes, such as on the well known band-aids.

The backing member 27 illustrated in FIGURES 10 and 11 may be sold per se to purchasers who have on hand the supply of conventional targets and who wish to apply the backing member to the targets themselves. The backing member 27 is applied to a conventional target, such as the target 10 of FIGURES 1 through 7, by removing the cover 30 and applying the adhesive-coated ribs 28 to the back of the target in line with the bull's-eye area of the target and pressing the same firmly thereagainst. It will be noted that the ribs 28 provide and define spaces 31 therebetween and the inner circular rib 28 defines a space 32 which spaces 31 and 32 are free of adhesive and when the backing member is applied to the rear of the target these spaces will be free from and spaced from the back surface of the target so that the material of these spaced areas is free to be stretched when penetrated by a bullet and will recover in the same manner as the backing members 14 and 22.

In FIGURE 12 a backing member 33 is illustrated and instead of the continuous circular ribs 28, the ribs are interrupted so as to provide concentric spaced apart rows of segments 34, the outer exposed surfaces of which are coated with a conventional adhesive 35, which is protected by a pull-off cover 36, similar to the cover 30 of FIGURES 10 and 11. It is apparent that when the pull-off cover 36 has been removed and the backing member 33 applied to the rear face of a conventional target the backing member will be attached to the target at spaced apart points so as to provide intervening areas of the backing member which are free of the target and which can expand when penetrated by a bullet.

The backing members 27 and 33 of FIGURES 10 through 12 when applied to the rear face of a conventional target will operate in the same manner as the target and backing member described and illustrated in FIGURES 1 through 9.

It is obvious that various other changes and modifications may be made in the details of construction and design of the above specifically described embodiments of this invention without departing from the spirit thereof, such changes and modifications being restricted only by the scope of the following claims. It is apparent from the above that this invention provides an optical safety target.

What I claim is:

1. A target backing member comprising a body of resilient material chosen from a group of natural rubber, silicone rubber, polyvinylchloride and polyethylene, raised portions carried on one side of said body, said raised portions having an exposed outer surface and an inner surface joined to said body, said raised portions constituting substantially less than a majority of the total surface area of one side of said body, and an adhesive applied to said exposed surfaces of the raised portions.

2. A tearable target sheet having scoring indicia thereon including a bull's-eye, a penetrable resilient backing member of a color contrasting to that of the said bull's-eye; securing means attaching said backing member to said target sheet at spaced-apart areas for allowing said target sheet to tear in the vicinity of a projectile impingement, thereby allowing the backing member to show through the hole made in the target sheet by the projectile and rendering the point of impingement more visible due to the contrast in color of the backing member to that of

the bull's-eye area, such backing member comprising a material characterized by the fact that it will stretch when being punctured by bullets passing through the target and the backing member so that the free portions of the backing member can stretch while the bullet is passing therethrough and can recover its original, unpunctured, unstretched condition save for a pinpoint opening in the center of the punctured area of the backing member after the bullet has passed therethrough, so that the portion defined by the spaced-apart areas of the backing member which have been penetrated by the bullet will be exposed through a portion of the target torn away by the passage of the bullet therethrough and will be visible to a person on the firing line due to the contrast in color of the backing member to that of the bull's-eye area.

3. A target as claimed in claim 2, in which the attaching means comprises a film of the same material as the backing member applied to the rear face of the target and the spaced apart areas of the backing member are hermetically sealed to the said film.

4. For use with a target, an elastic backing member adapted to be secured to the back of the target, and means on the backing member for securing spaced apart areas of the backing member to the back of the target, said backing member comprising a material having the ability to stretch when being punctured by a projectile passing through the target and to return to its original unpunctured, unstretched condition save for a small opening therein in the punctured area of the backing member after the projectile has passed therethrough, said small opening being significantly smaller than the projectile passing therethrough, said backing member material being chosen from the group consisting of natural rubber, silicone rubber, polyvinylchloride and polyethylene.

5. A backing member as claimed in claim 4, in which the securing means is an adhesive arranged in spaced apart concentric circles on the backing member.

6. A backing member as claimed in claim 5, in which a removable cover is positioned over the adhesive bearing areas on the backing member to protect the adhesive from air, moisture and extraneous matter.

7. A backing member as claimed in claim 4, in which the securing means is an adhesive arranged in spaced apart segments of concentric interrupted circles.

8. A backing member as claimed in claim 7, in which a removable cover is disposed over the adhesive bearing areas of the backing member to protect the adhesive from air, moisture and extraneous matter.

9. For use with a target, an elastic backing member adapted to be secured to the back of the target, and means on the backing member for securing spaced apart areas of the backing member to the back of the target, said backing member comprising a material having the ability to stretch when being punctured by a projectile passing through the target and to return to its original unpunctured, unstretched condition save for a small opening therein in the punctured area of the backing member after the projectile has passed therethrough, said small opening being significantly smaller than the projectile passing therethrough, said backing member material having a Shore A scale durometer reading in the range of 10 to 75.

10. For use with a target, an elastic backing member adapted to be secured to the back of the target, and means on the backing member for securing spaced apart areas of the backing member to the back of the target, said backing member comprising a material having the ability to stretch when being punctured by a projectile passing through the target and to return to its original unpunctured, unstretched condition save for a small opening therein in the punctured area of the backing member after the projectile has passed therethrough, said small open-

ing being significantly smaller than the projectile passing therethrough, said backing member material having a Shore D scale durometer reading in the range of 40 to 68.

11. For use with a target, an elastic backing member adapted to be secured to the back of the target, means on the backing member for securing spaced apart areas of the backing member to the back of the target, said backing member comprising a material having the ability to stretch when being punctured by a projectile passing through the target and to return to its original unpunctured, unstretched condition, save for a small opening therein in the punctured area of the backing member after the projectile has passed therethrough, said small opening being significantly smaller than the projectile passing therethrough, said backing member having on one face thereof ribs arranged in concentric spaced apart circles, a means for securing the backing member to the target being on the ribs, and a pull-off protective cover disposed over the ribbed face of the backing member.

12. For use with a target, an elastic backing member adapted to be secured to the back of a target, means on the backing member for securing spaced apart areas of the backing member to the back of the target, said backing member comprising a material having the ability to stretch when being punctured by a projectile passing through the target and to return to its original unpunctured, unstretched condition save for a small opening therein in the punctured area of the backing member after the projectile has passed therethrough, said small opening being significantly smaller than the projectile passing therethrough, said backing member having on one face thereof ribs arranged as segments of interrupted spaced apart concentric circles, the means for securing the backing member to the target being placed upon said segments, and a pull-off protective cover disposed over the ribbed face of the back member.

13. For use with a target sheet having a colored face, a substantially planar elastomeric backing member having means for securing said backing member to the rearward face of a conventional target sheet in a designedly patterned manner leaving substantial areas of said backing member free from engagement with the target sheet, said backing member having a Shore A durometer reading in the range of 10 to 75.

14. For use with a target sheet having a colored face, a substantially planar elastomeric backing member having means for securing said backing member to the rearward face of a conventional target sheet in a designedly patterned manner leaving substantial areas of said backing member free from engagement with the target sheet, said securing means including raised portions on a face of said backing member.

15. For use with a target sheet having a colored face, a substantially planar elastomeric backing member having means for securing said backing member to the rearward face of a conventional target sheet in a designedly patterned manner leaving substantial areas of said backing member free from engagement with the target sheet, said elastomeric backing member being of the group of natural rubber, silicone rubber, polyvinylchloride and polyethylene.
